MOBILE WIND MACHINE FOR FROST PROTECTION OF LOW GROWING CROPS

Kermit J. Nutt, 100 N. Catalina St.,
Los Angeles, Calif. 90004

Filed Oct. 23, 1965, Ser. No. 87,873

Term of patent 14 years

(Cl. D62—2)

FIG. 2.

FIG. 3.

FIG. 4.

FIGURE 1 is a perspective view of the mobile wind machine for frost protection of low growing crops, showing my new design;

FIGURE 2 is a top plan view thereof;

FIGURE 3 is a front elevational view thereof, looking in the direction of the propeller; and,

FIGURE 4 is a side elevational view thereof.

I claim:

The ornamental design for a mobile wind machine for frost protection of low growing crops, substantially as shown.
